CLAIM

The ornamental design for a rip fence and cutting guide, as shown and described.

DESCRIPTION

FIG. 1 is a top plan view of a rip fence and cutting guide showing our new design;

FIG. 2 is a side elevational view thereof, the opposite side elevational view being a mirror image thereof;

FIG. 3 is a bottom plan view thereof;

FIG. 4 is a front elevational view thereof;

FIG. 5 is a back elevational view thereof; and,

FIG. 6 is a cross-sectional view taken along line 6—6 of FIG. 3.
